UNITED STATES PATENT OFFICE.

MATTHEW LUCKIESH, OF CLEVELAND, OHIO.

LIGHTING FIXTURE.

Application filed December 30, 1925. Serial No. 78,267.

The present invention relates to lighting fixtures, and is more particularly directed toward a form of lighting fixture for house lighting, and is provided with separately controlled lamps, one of which is arranged for the illumination of a table directly underneath the fixture, while the other lamps may be controlled to illuminate the room both by light diffused through a surrounding bowl and by light directed toward the ceiling.

An object of the present invention is to provide such a lighting fixture in which a glass bowl is associated with the lamps in such a way that the bowl may be swung downwardly to provide access to the lamps without affecting the reflector.

Another object of the invention is to provide a fixture which may be provided with a glass inclosing bowl of pleasing design and ornamentation, and to so mount the bowl that it is protected against injury.

A further object of the invention is to provide a lighting fixture of this type having the hinge and catch mechanism hidden by an ornamented part of the fixture.

Other and further objects of the invention will appear as the description proceeds.

The accompanying drawing shows for purposes of illustration, one of the many possible forms in which the present invention may be embodied, it being understood that the drawings are merely illustrative of the invention, which may be embodied in various forms.

In these drawings:

Fig. 1, is an elevational view, with parts in section, showing the lighting fixture with the glass bowl in the elevated position;

Fig. 2, is an elevational view of the lighting fixture, showing in dotted lines the position assumed when the glass bowl is lowered;

Fig. 3, is a diagrammatic plan view of the lighting fixture, parts being omitted;

Fig. 4, is an enlarged view of the central part of the fixture, parts being an elevation and other parts in section;

Fig. 5, is an enlarged sectional view taken on the line 5—5 of Fig. 1;

Figs. 6 and 7, are sectional views taken on the lines 6—6, and 7—7, respectively, of Fig. 5 and showing the hinge and catch mechanisms; and

Fig. 8, is a sectional view taken on the line 8—8, of Fig. 1.

The present lighting fixture may be sup-

ported in any suitable manner, but for convenience, it is here shown as being supported at the lower end of a hanger rod or pipe 10, which is threaded into a hickey 11. A 60 body member 12, is provided with a vertical hole 13, so that it may be passed downwardly over the pipe 10. This body member supports a plurality of arms 14 in any suitable manner. For convenience, these arms may be threaded into the body member as indicated at 15. The outer ends 16 of these arms are attached to and support a frame 17 which extends around the fixture. This frame is here shown as being hexagonal in form. A 70 movable frame 18 surrounds the fixed frame 17, and is suitably attached to it by means of a hinge 19 and a catch mechanism such as a screw 20, arranged on the opposite side of the frame. In order that the fixture may 75 have a more ornamental appearance, the frame 18 is provided with a number of ornaments 21 which extend upwardly as indicated. These ornaments may be such as to completely conceal the hinge and to render 80 the catch unnoticeable. The frame is also provided with a number of depending members 22, which may be attached to the corners of the frame 18 by screws 23. The lower ends of these members may be bent inwardly 85 as indicated at 24 and teardrops 25 attached as indicated. These depending members serve not only as ornamental features of the fixture, but along with the frame or ring 18 provide a convenient support for a glass bowl 26, which may be inserted into the frame from above and held in place by clips 27, indicated in Figs. 6 and 7.

The arrangement so far described, provides a convenient support for carrying 90 the glass bowl in such a manner that it can be swung from the full line position of Fig. 2, down to the dotted line position, thereby providing access to the parts of the fixture ordinarily carried inside of the 100 glass bowl.

When a fixture of the above type is to be provided with a single lamp to give downward illumination and plurality of lamps to give general illumination, one may use 105 the arrangement illustrated in Figs. 1 and 4. Here a lamp socket 27' is attached to the lower end of a hickey 11 and this lamp socket is adapted to carry a lamp 28 which extends downwardly along the axis of the fixture. 110 In order that the light from this lamp may be directed downwardly, as onto a table,

and not onto the glass bowl, there is provided a suitable reflector 29, supported at the lower end of a shell 30. As here shown this shell is in the form of an inverted cup shaped 5 stamping, provided with a hole 31 so that the lower end of hickey 11 may pass through, and with a number of holes 32 to accommodate the lead wires. In order to reinforce the construction a number of washers 33 are 10 placed between the upper end of the lamp socket and the upper end of the socket cover. To provide a finished appearance in the lighting fixture, the stamping 30 is recessed as indicated at 34 and a stamping 34' is 15 slidably carried on the lower end of the body member 12. This stamping will act as a cover member for the wires which come out from the hickey to supply the outer lamps, to be described.

20 V-shaped brackets 35 are fastened to the upper end of the shell 30 and provide supports for a number of electric lamp sockets 36, which project obliquely downward and surround the central lamp socket 27'. The 25 lamps 37, carried in the sockets 36, are preferably located slightly below the frame 17. These lamps are adapted to illuminate the glass bowl 26, which will diffuse the light downwardly and reflect a part of it toward 30 the ceiling. These lamps may be connected by wires carried out through the hickey as indicated.

While the lower part of the glass bowl may be closed, if desired, it is preferable for 35 ornamentation purposes and in order to provide access to the central lamp 28, that a central opening be provided in the glass bowl. This opening is indicated at 38. The lower end of the light unit may be conveniently finished off by a stamping 39 which 40 covers the lower end of the glass bowl 26 and which extends up through the opening 38. The stamping is held in place by a corrugated ring 40 which has projections 41 resting 45 on the upper surface of the glass bowl underneath the lower end of the reflector. The stamping 39 may carry a number of ornaments 42, if desired. The central lamp 28 may be controlled by means of a pull cord 50 43 which operates the switch in the socket 27'. The outer lamps 37 may be controlled by a canopy switch, or otherwise as desired.

From the foregoing it will be apparent 55 that one is able to obtain direct illumination from the central lamp when it is desired to light a table, or the like, directly underneath the fixture. When, however, one desires to obtain general illumination in the room, the upper lamps may be switched on. 60 These lamps may operate with or without the central lamp. They will be concealed by the glass bowl, and an even, pleasing, illumination will result. The light will be reflected from the inner surface of the glass bowl and from the outside of the reflector 65

29 in such a manner that the reflector will not be apparent when looking at the fixture. The central lamp may be removed readily, and access is provided to the outer lamps for replacement or cleaning, by merely un- 70 loosening the catch screw 20 and swinging the bowl downward to the position indicated in dotted lines in Fig. 2.

It is preferable that the opening 38 be 75 comparatively small so that it will be possible to hang the lighting unit higher than is ordinarily possible in dining room fixtures. By making the opening small it is possible to raise the unit without bringing the lamp filaments into the line of vision of the diners 80 thereby avoiding the objections to low hung fixtures in common use. By making this aperture small there also results a better control of the light confining it chiefly to the table. This is of particular advantage when the daylight lamp is used in the inner reflector for the downward light, as the artificial 85 daylight is confined to the table. A warmly tinted glass bowl emits a light of a warmer color to the face of the diners and the walls, 90 ceilings and other parts of the room.

It is obvious that the invention may be embodied in many forms and constructions within the scope of the claims, and I wish 95 it to be understood that the particular form shown is only one of the many forms. Various modifications and changes being possible, I do not otherwise limit myself in any way with respect thereto.

I claim:

1. In a lighting fixture the combination with a glass bowl open at the top, and a bowl supporting frame about the top of the bowl, of a fixed frame, a hinge connection between the frames, a support for the fixed frame, a single downwardly extending lamp socket supported from the frame, a downwardly opening reflector disposed inside said bowl, and about the lamp socket and a plurality of obliquely disposed lamp sockets carried from the support and adapted to carry lamps inside said bowl, the frame and bowl being capable of being swung downwardly to clear the obliquely disposed lamps and the reflector.

2. In a lighting fixture, a fixed ring, a ring carried outside the fixed ring, a hinge interconnecting the rings at one side, a catch interconnecting them at the opposite side, a plurality of ornaments carried by the outer ring to conceal the hinge and catch, a plurality of depending numbers attached to the outer ring, the lower ends of said numbers being carried inwardly, and a glass bowl carried by the outer ring and depending 115 numbers.

3. A lighting fixture having a plurality of lamps carried about one centrally disposed downwardly directed lamp, a reflector for the central lamp, a glass bowl open at 130

the top and surrounding the lamps and reflector, said bowl being adapted to diffuse the light and to reflect a portion of it upwardly, and supporting means of the bowl whereby it can be swung downwardly to give access to the outer lamps.

4. A lighting fixture having a support, a plurality of lamp sockets carried underneath the support, the central lampsocket being directed vertically downward, a downwardly opening reflector for said central lamp socket, a frame fixedly carried from said support and surrounding the lamps carried in the other lamp sockets, a second frame hinged to one side of the fixed frame, and a glass bowl carried by the hinged frame and surrounding all the lamps and the reflector.

5. In a lighting fixture a plurality of lamps carried about a center, a glass bowl open at the top, said bowl surrounding the lamps and having its upper edge above the plane of the lamps, a downwardly directed reflector associated with a single lamp socket, and means for hingedly supporting the bowl so that it can be swung downwardly to be clear of the lamps and reflector.

6. In combination, a glass lighting fixture bowl having a supporting ring about its upper outer edge, and a plurality of lamps fixedly carried inside the bowl, a downwardly opening reflector associated with one of the lamps, and hinge connections for the ring to permit lowering the bowl to give access to the lamps.

7. In a lighting fixture a body member, a lamp socket carried directly underneath the body member, a plurality of obliquely disposed lamp sockets carried below the body member, a shell carried outside the first mentioned socket, a reflector carried by the shell and adapted to surround the lamp in the first mentioned socket, a plurality of arms extending outwardly from the body member, a ring carried by the arms, a frame carried outside the ring and hinged to the ring, and a glass bowl carried by the frame and surrounding all the lamps.

8. In a lighting fixture a body member, a lamp socket carried directly underneath the body member, a plurality of obliquely disposed lamp sockets carried below the body member, a shell carried outside the first mentioned socket, a reflector carried by the shell and adapted to surround the lamp in the first mentioned socket, a plurality of arms extending outwardly from the body member, a ring carried by the arms, a frame carried outside the ring and hinged to the

ring, and a glass bowl carried by the frame and surrounding all the lamps, the glass bowl having an opening underneath the reflector.

9. In a lighting fixture, a glass bowl having a central opening in the bottom thereof, a metal frame about the upper rim of the bowl, a fixedly supported frame hingedly connected to the first frame, and a plurality of lamps carried by the fixed frame, one lamp being directly above the opening in the bowl, and a plurality of depending members attached to the frame, the lower ends of said depending members being inwardly directed to provide supports for the bowl.

10. In a lighting fixture, a glass bowl, a metal frame about the upper rim of the bowl, a fixed frame having a ring carried inside the bowl supporting frame and concealed thereby, and hinge connections between the frames, and a plurality of depending members attached to the frame, the lower ends of said depending members being inwardly directed to provide supports for the bowl.

11. A lighting unit for dining rooms, said unit being provided with a centrally disposed downwardly directed lamp provided with a reflector adapted to concentrate the light from said lamp onto a table and render the lamp filaments invisible from outside the table, a plurality of lamps outside the reflector, and a glass bowl open at the top and surrounding the reflector and outer lamps, said bowl acting to diffuse the light from the outer lamps and reflect a portion of it upwardly, the bowl being open above the reflector.

12. A lighting unit for dining rooms, said unit being provided with a centrally disposed downwardly directed lamp provided with a reflector adapted to concentrate the light from said lamp onto a table and render the lamp filaments invisible from outside the table, a plurality of lamps outside the reflector, a glass bowl open at the top and surrounding the reflector and outer lamps, said bowl acting to diffuse the light from the outer lamps and reflect a portion of it upwardly, the bowl being open above the reflector, and supporting means for the bowl to permit it to be swung downwardly to give access to the outer lamps.

Signed at Cleveland, in the county of Cuyahoga, and State of Ohio, this 24th day of December, 1925.

MATTHEW LUCKIESH.
